ORNAMENTAL STITCH SEWING MACHINE

Frederic M. Card, Bridgeport, Conn., assignor to
The Singer Manufacturing Company, Elizabeth, N. J., a corporation of New Jersey

Application April 1, 1939, Serial No. 265,397

13 Claims. (Cl. 112—98)

This invention relates to sewing machines and more particularly to ornamental stitching machines, the invention having for its primary object to provide a quiet running high-speed ornamental stitching machine.

A more specific object of the invention is to eliminate from ornamental stitching machines the wear and noise incidental to the use of pattern-cams heretofore employed in said machines for controlling the stitch-forming and work-feeding mechanisms thereof.

Another object of the invention is to provide an ornamental stitching machine with conveniently regulatable means for producing various ornamental stitching effects of different configuration. Still further objects of the invention will be apparent from the following description and claims.

The invention consists in the needle and feed actuating and controlling mechanism of sewing machines as hereinafter described in connection with the accompanying drawings which illustrate a preferred embodiment of the invention and in which:

Fig. 1 represents a vertical longitudinal section, partly in front elevation, of the improved ornamental stitching machine. Fig. 2 represents a bottom plan view of the machine. Fig. 3 represents a vertical section through the bracket-arm standard of the machine on substantially the line 3—3 of Fig. 1. Fig. 4 represents a cross-section through the bracket-arm to include both of the cross-shafts which carry the needle-vibration and feed-controlling eccentrics. Fig. 5 is a detail view in front elevation of the feed-indicator disks. Fig. 6 is an enlarged detail view of the needle-vibration controlling connections, with the controlling eccentric therefor illustrated diagrammatically in the timing thereof for producing fagoting stitches. Fig. 7 is a diagrammatic illustration of fagoting stitches which may be produced by the machine, when the needle-vibration controlling eccentric is timed as shown in Fig. 6. Fig. 8 illustrates, diagrammatically, several of various kinds of ornamental stitching effects which may be produced by the machine, by merely changing the relative timing of the needle and feed-controlling eccentrics. Fig. 9 is a diagrammatic representation of the feed-controlling connections.

The sewing machine illustrated in the drawings has the usual work-supporting bed-plate 1, from one end of which rises the tubular standard 2 of a bracket-arm 3 which overhangs the bed-plate 1 and terminates at its free end in a head 4.

Rotatably journaled in the bracket-arm 3, to extend horizontally lengthwise thereof, is a main actuating or needle-reciprocating shaft 5 carrying at one end a belt-pulley 6. At its opposite end, the shaft 5 carries a counterbalanced crank-disk 7 connected by the usual link 8 with a vertically disposed needle-bar 9 carrying at its lower end a needle 10.

The needle-bar 9 is journaled for endwise reciprocation in a laterally swinging frame 11 pivotally hung at its upper end upon a fulcrum-pin 12 within the bracket-arm head 4. The frame 11 is, as usual, provided adjacent its lower end with an arcuate slot 13 to receive a guide-stud 14, and is also pivotally connected by a screw 15 to one end of a needle-bar vibrating pitman 16. At its opposite end, the pitman 16 has a split strap 17 embracing a rotary needle-vibrating eccentric 18 constructed substantially as more fully disclosed in the U. S. patent to C. F. Gray, No. 1,020,089, Mar. 12, 1912. In general, the eccentric 18 has an enlarged shaft-aperture 19 and extends laterally from a frame 20 adjustably carried by a disk 21 secured by a screw 22 upon a cross-shaft 23. The cross-shaft 23 is disposed below and substantially normal to the needle-reciprocating shaft 5, being journaled at the front of the bracket-arm 3 in a bearing provided by a detachable cap-plate 24 and at its rearward end in a frame-boss 25. Adjacent the eccentric 18, there is secured to the cross-shaft 23 a gear-wheel 26 driven by a worm-gear 27 carried by the needle-reciprocating shaft 5.

The worm-gear 27 is preferably secured upon the shaft 5 to provide for angularly adjusting said worm-gear 27, thereby to change the timing of the eccentric 18. To this end, the worm-gear 27 has a hub 28 extending into an annularly recessed collar 29 secured by screws 30 upon the shaft 5, said collar 29 being secured to the gear-hub 28 by set-screws 31. By freeing the set-screws 31, the shaft 5 and worm-gear 27 may be relatively rotated to change the timing of the eccentric 18, the gear-hub 28 being preferably provided with spanner-apertures 32 to receive a suitable tool for effecting adjustment of the worm-gear 27.

In the present case, the ratio of the gears 26 and 27 is such that the cross-shaft 23 rotates once for six rotations of the needle-reciprocating shaft 5. Consequently, the needle 10 reciprocates six times in each complete rotation of the eccentric 18, i. e., the needle reciprocates three times while moving laterally in one direction and three times in its return lateral movement to complete a six-stitch cycle. The amplitude of the complete

lateral vibration of the needle or, in other words, the width of the ornamental seam is determined by adjustment of the eccentricity of the eccentric 18, which may be effected by means of the usual regulating spindle 33, as disclosed in said prior Patent No. 1,020,089.

Cooperating with the needle 10, in the formation of lock-stitches, is a loop-taker in the form of the usual rotary hook 34 having its axis of rotation substantially parallel to the cross-shaft 23, whereby the rotary hook beak rotates in a plane parallel to the plane of lateral vibration of the needle. The rotary hook 34 is carried by a shaft 35 rotatably journaled in a bushing 36 secured in a lug 37 at the under side of the bed-plate 1. Suitably secured to the hook-shaft 35 is a bevel-gear 38 in mesh with a similar gear 39 carried by one end of a rotary hook actuating shaft 40. The shaft 40 extends horizontally lengthwise of the bed-plate 1 and is journaled for rotation in a tubular feed-lift rock-shaft 41 which, in turn, is journaled to rock in spaced bearing-lugs 42 and 43 depending from the bed-plate 1. At its end opposite to the bevel-gear 39, the hook actuating shaft 40 carries a pulley 44 connected by a clip-belt 45 to a pulley 46 carried by the needle-reciprocating shaft 5, the pulleys 44 and 46 being proportioned so that the hook-actuating shaft 40 rotates twice for each rotation of its driving shaft 5.

The work is advanced by a feed-dog 47 of the drop-feed type, said feed-dog being opposed by a suitable presser-foot and operating through slots provided in a throat-plate 48, secured upon the bed-plate 1 and having the usual needle-slot 49. The feed-dog 47 is carried by a feed-bar 50 having a slot 51 receiving a slide-block 52 connected by a pivot-bolt 53 to a crank-arm 54 clamped upon one end of the feed-lift rock-shaft 41. Secured upon said feed-lift rock-shaft 41, at the opposite end thereof, is a crank-arm 55 connected by a pivot-bolt 56 to the lower end of a pitman 57. The pitman 57 extends upwardly within the arm-standard 2 and has, at its upper end, a strap embracing a feed-lift eccentric 58 carried by the actuating shaft 5. It will therefore be understood that the feed-dog 47 is raised and lowered once for each reciprocation of the needle.

The rearward end of the feed-bar 50 is pivotally supported by and between the upstanding arms 59 at one end of a feed-advance rock-shaft 60, disposed in substantial parallelism with the feed-lift rock-shaft 41 and journaled in bearing-lugs 61 and 62 depending from the bed-plate 1. Clamped upon the opposite end of the feed-advance rock-shaft 60 is a depending crank-arm 63 connected by a pivot-bolt 64 to one end of a link 65, of which the opposite end is connected by a pivot-bolt 66 to a slide-block 67. The slide-block 67 is shiftable disposed in a segmental guideway 68 provided in a rocking-member 69 having a fulcrum-pin 70 extending laterally from said member substantially medianly between the ends thereof. The fulcrum-pin 70 is journaled for rocking movements in an apertured boss 71 at the lower end of a bracket 72 secured by screws 73 to the under side of the bed-plate 1.

The rocking-member 69 has an ear 74 to which 70 is pivotally secured, by a screw 75, the lower end of a pitman 76. At its upper end, the pitman 76 has a strap embracing an adjustable feed-advance eccentric 77 carried by the needle-reciprocating shaft 5. The adjustable eccentric 77 75 is constructed, in the present case, substantially

in accordance with the disclosure in the U. S. patent to J. H. Stearns, No. 2,029,278, Jan. 28, 1936, although any other suitable or desired form of adjustable eccentric may be employed. From the foregoing description, it will be understood that the feed-dog 47 derives work-advancing and return movements of variable amplitude from the eccentric 77 and that said work-advancing movements are timed to occur when the feed-dog 47 is raised by the feed-lift mechanism actuated by 10 the feed-lift eccentric 58.

In order to control the effective action of the feed-dog 47 automatically, the slide-block carrying link 65 is connected by a ball-joint 78 to the lower end of a link 79 reciprocating endwise within the arm-standard 2. At its upper end, the link 79 is connected by a ball-joint 80 to an arm 81 of a two-armed lever 81, 82 fulcrumed upon a pivot-screw 83 threaded into the inner wall of the bracket-arm 3, the fulcrum-axis of the lever 81, 82 being substantially parallel to the cross-shaft 23. The arm 82 of the lever 81, 82, is pivotally connected to the lower end of a pitman 84 having a strap 85 embracing a feed-controlling eccentric 86. As illustrated more particularly in Fig. 4 of the drawings, the eccentric 86 is secured by a set-screw 87 upon a shouldered cross-shaft 88 journaled at its rearward end in a bushing 89 suitably fixed in an aperture in the rear wall of the bracket-arm 3, the cross-shaft 88 30 being disposed above the needle-reciprocating shaft 5 and in substantial parallelism with the cross-shaft 23. The forward reduced portion of the cross-shaft 88 is journaled in a shaft-sleeve 90 which is itself journaled for rotation in a bearing-bushing 91 suitably fixed in the front wall of the bracket-arm 3.

Secured upon the sleeve 90, by a set-screw 92, is the hub 93 of a spiral gear 94 in mesh with a spiral pinion 95 suitably secured upon the needle-reciprocating shaft 5, the ratio of the gears 94 and 95 being such that the cross-shaft 88 rotates once for three rotations of the needle-reciprocating shaft 5. The spiral gear 94 preferably has its side face annularly recessed adjacent the feed-controlling eccentric 86 to receive a disk-flange 45 96 of said eccentric.

At the front side of the bracket-arm 3, the shaft-sleeve 90 has a disk-flange 97 preferably having a beveled indexed periphery and provided with a series of apertures 98. Adapted to releasably enter any one of said apertures 98 is a coupling-pin 99 extending from a side face of a coupling-disk 100 secured by a key 101 upon the shaft 88 for rotation therewith, but permitting limited movement of the coupling-disk 100 endwise of said shaft. The coupling-disk 100 has a knurled head 102 centrally apertured to receive the head 103 of a screw threaded into the forward end of the cross-shaft 88, the screw-head 103 serving as an abutment for a spring 104 which functions to hold the coupling-disk 100 yieldingly in contact with the disk-flange 97, with the coupling-pin 99 disposed in one of the disk-flange apertures 98. By uncoupling the disk-flange 97 and coupling-disk 100, the cross-shaft 88 may be turned to change the timing of the eccentric 86, as will be self-evident. An angular cover-plate 105 is detachably secured upon the bracket-arm 3 and provides for access to the mechanism within the bracket-arm.

The sewing machine hereinbefore described is particularly adapted for producing ornamental stitching, commercially known as fagoting. As illustrated diagrammatically in Fig. 7 of the 75

drawings, fagoting comprises successive repetitions of a six-stitch figure, (1) a stitch *a* made by vibrating the needle **10** laterally in one direction while the work is fed backwardly; (2) a succeeding and longer stitch *b* made by further vibrating the needle laterally in the same direction while the work is fed forwardly; (3) a succeeding stitch *c* of substantially the same length as stitch *a* made by still further vibrating the needle laterally in the same direction, while the work is fed forwardly; (4) a stitch *d*, of substantially the same length as stitch *a*, made while the needle vibrates in the return or opposite direction and the work is fed backwardly; (5) a longer stitch *e*, of substantially the same length as stitch *b*, made by continuing the return vibration of the needle and feeding the work forwardly; and (6) a shorter stitch *f*, of substantially the same length as stitch *a*, made by completing the return vibration of the needle while the work is again fed forwardly. From this description, it will be understood that, in producing fagoting, the work is fed twice forwardly and once backwardly in each direction of lateral movement of the needle **10**.

While the fagoting seam above described is well known in the art, the prior sewing machines constructed to produce fagoting seams were provided with suitably timed pattern-cams having follower-guiding tracks of the requisite shapes to vibrate the needle laterally and to control the feeding of the work. These pattern-cams imposed definite limitations to the maximum speed of operation of the machines and to the varieties of ornamental seams capable of being produced with the respective cams in the machine.

In the present machine, as hereinbefore structurally described, the needle vibrations are derived from an eccentric and the requisite work-feeding movements of the feed-dog are likewise controlled by an eccentric. While it has been old in the art to employ an eccentric for vibrating a needle-bar laterally so that the needle reciprocated once in each direction of lateral movement thereof, the present eccentric arrangement provides for so vibrating the needle laterally that the needle reciprocates a plurality of times in each direction of lateral movement thereof, and still further provides for the production of stitches of unequal lengths in each direction of lateral movement of the needle.

Likewise, instead of employing a pattern-cam for controlling the effective operation of the feed-dog, the described feeding mechanism is so designed that in one complete rotation of a feed-controlling eccentric the work is fed twice forwardly and once backwardly. By employing eccentrics for the purposes described, instead of pattern-cams, the speed of operation of the machine may be substantially increased beyond the maximum speed capacity of prior machines while, at the same time, reducing objectionable noise and wear. Furthermore, by the provision for convenient adjustments of the relative timing of the needle-vibrating and feed-controlling eccentrics, a large variety of ornamental seams may be readily produced.

Referring now more particularly to Fig. 6 of the drawings, for the production of fagoting stitches the needle-vibrating eccentric **18** is so timed that its point of maximum eccentricity has an angular movement *a'* during the formation of the stitch *a* of Fig. 7, and successive angular movements *b', c', d', e', f'* in the forma-

tion of the remaining stitches *b, c, d, e, f*, respectively, of the seam. While said angular movements of the point of maximum eccentricity are equal, it will be noted that the effective needle-vibrating components of the angular movements *b'* and *e'*, while substantially equal to each other, are longer than the effective, substantially equal needle-vibrating components *a', c', d'* and *f'*. By relating the lengths of said effective components to the stitches comprising a fagoting cycle, it will be observed that the eccentric functions to vibrate the needle **10** so as to produce four relatively short stitches *a, c, d* and *f* of substantially equal length and two relatively longer stitches *b* and *e*, of substantially equal length, in each complete fagoting cycle.

The length of the stitches is not only dependent upon the amplitude of lateral vibration of the needle **10** between successive work-penetrations thereof, but also upon the feeding mechanism which is illustrated diagrammatically in Fig. 9 of the drawings. The feed-dog **47**, carried by the feed-bar **50** is, as usual, raised and lowered by the feed-lift eccentric **58** having the described connections with the slide-block **52**, and forward and backward movements are imparted to said feed-dog **47** by the feed-advance eccentric **11** which functions to rock the segmental guideway **68** about its fulcrum-axis **70**. In any off-center position of the slide-block **61** in its guideway **68**, the rocking movements of said guideway are transmitted by the link **65** to the feed-rocker **59, 60, 63**, as will be readily understood.

The shifting movements of the slide-block **61** in the guideway **68** are controlled by the feed-controlling eccentric **86** through the described connections with said slide-block **61**, the throw of the eccentric **86** being such that the slide-block **61** travels from one side to the other of the fulcrum-axis **70** of the guideway **68**. When the feed-controlling eccentric **86** is timed for producing fagoting work, the point of maximum eccentricity of the eccentric **86** has a position *x* in a median position of the feed-dog **47** in one forward work-advancing movement thereof. In said position *x* of the eccentric **86**, the slide-block **61** is substantially at *x'* in the portion of the guideway **68** above the fulcrum-axis thereof. In a one-third revolution of the eccentric **86**, from the position *x* to position *y* of its point of maximum eccentricity, the slide-block **61** travels downwardly across the fulcrum-axis **70** in the guideway **68**, during the return idle movement of the feed-dog **47**, to bring said slide-block to the point *y'* in the succeeding median position of the feed-dog **47** in which the work is fed backwardly.

In the next one-third revolution of the eccentric **86**, from *y* to *z*, the slide-block travels upwardly across the fulcrum-axis **70** of the guideway **68** to substantially the point *z'*, during the time that the feed-dog **47** has its return idle movement to a median position of forward feeding movement. In the final one-third revolution of the eccentric **86**, from *z* to the starting point *x*, the slide-block **61** travels slightly upwardly and then downwardly to the position *x'* thereof wherein the feed-dog **47** is again advancing the work forwardly.

From the foregoing, it will be understood that for fagoting work, the feed-controlling eccentric **86** has its point of maximum eccentricity substantially at *y* to control the feed-dog **47** so that

it feeds the work backwardly during a portion of the time when the needle-vibrating eccentric 18 has its angular movement a' , Fig. 6, to form the short backward stitch a , Fig. 7. Also, that when the feed-controlling eccentric point is at z , the work is fed forwardly during a portion of the time when the needle-vibrating eccentric 18 has its angular movement b' to form the relatively longer stitch b . Still further, that when the feed-controlling eccentric point is at x , the work is again fed forwardly during a portion of the time when the needle-vibrating eccentric 18 has its angular movement c' to form the succeeding shorter stitch c . During the remaining half of the fagoting cycle, the above described control of the feed-dog 47 is repeated, as will be self-evident.

Obviously, the width of the fagoting seam may be conveniently changed by merely adjusting the eccentricity of the needle-vibrating eccentric 18, by means of the eccentric-adjusting spindle 33. Also, the lengths of the stitches may be conveniently changed by adjusting the eccentricity of the feed-advance eccentric 17, whereby the amplitude of rocking movement of the guideway 68 may be increased or decreased.

In addition to fagoting work, the present machine may be readily set for producing a large variety of ornamental seams, a few of which seams are illustrated in Fig. 8 of the drawings. Different varieties of seams may be produced by merely changing the timing of the needle-vibrating eccentric 18, which as before described may be accomplished by freeing the eccentric-driving worm-gear 27 from the shaft 5 and turning said worm-gear upon said shaft. Other varieties of seams may be produced by merely adjusting the timing of the feed-controlling eccentric 86, which as also before described may be conveniently effected by pulling forwardly upon the coupling-disk head 102, partly turning the feed-controlling cross-shaft 88 and recoupling the disks 97, 100, in a newly selected relative position thereof. By means of any suitable indicator-expedient, the desired relative position of the disks 97, 100, may be obtained with precision.

Still further varieties of ornamental seams may be produced by adjusting the timing of both the needle-vibrating eccentric 18 and the feed-controlling eccentric 86, as will be apparent. In connection with the timing adjustments described, it is to be understood that said adjustments do not interfere with the complementary action of the reciprocating needle 10 and rotating loop-taker 34 to form stitches. The loop-taker 34 accommodates the maximum lateral throw of the needle 10 effected by the needle-vibrating eccentric 18 of the machine. For still wider lateral throws of the needle, any well-known or other suitable device may be employed either to accelerate and retard the loop-taker or to bodily shift the loop-taker laterally in timed relation with the needle.

It is also to be understood that the timing adjustments of the feed-controlling eccentric 86 do not interfere with the proper feeding of the work, because the timing of the rocking-member 69 to actuate the feed-dog 47 and the timing of the feed-lift mechanism is unaffected by said timing adjustments of the feed-controlling eccentric 86.

Having thus set forth the nature of the invention what I claim herein is:

1. In a sewing machine, an endwise reciprocating and laterally vibratory needle-bar, a

swinging frame in which said needle-bar is journaled for endwise reciprocation, a rotary needle-vibrating eccentric, a strap embracing said eccentric and operatively connected to swing said frame laterally, means for rotating said eccentric, and means for reciprocating said needle-bar a plurality of times in each direction of lateral vibration of said frame. 5

2. In a sewing machine, stitch-forming mechanism including an endwise reciprocator and laterally vibratory needle-bar, a swinging frame in which said needle-bar is journaled for endwise reciprocation, means for reciprocating said needle-bar, a rotary needle-vibrating eccentric, a strap embracing said eccentric and operatively connected to swing said frame laterally, and means for rotating said eccentric in angularly timed relation to the reciprocations of said needle-bar to effect the production of relatively long and short stitches in each direction of lateral movement of said needle-bar. 10 15

3. In a sewing machine, an endwise reciprocator and laterally vibratory needle-bar, a swinging frame in which said needle-bar is journaled for endwise reciprocation, a rotary needle-reciprocating shaft, operative connections with said shaft for reciprocating said needle-bar, a rotary needle-vibrating eccentric, means actuated by said eccentric and operatively connected to swing said frame laterally, and means 25 30 for rotating said eccentric at one-sixth the speed of rotation of said needle-reciprocating shaft.

4. In a sewing machine, an endwise reciprocator and laterally vibratory needle-bar, a swinging frame in which said needle-bar is journaled for endwise reciprocation, a rotary needle-vibrating eccentric, means actuated by said eccentric and operatively connected to swing said frame laterally, means for reciprocating said needle-bar a plurality of times in each direction of lateral vibration of said frame, and driving connections for rotating said eccentric including means providing for adjustment of the timing of the eccentric. 35 40

5. In a sewing machine, an endwise reciprocator and laterally vibratory needle-bar, a swinging frame in which said needle-bar is journaled for endwise reciprocation, a rotary needle-reciprocating shaft, operative connections with said shaft for reciprocating said needle-bar, a rotary needle-vibrating shaft disposed crosswise of said needle-reciprocating shaft, an eccentric carried by said needle-vibrating shaft, a pitman having at one end a strap embracing said eccentric and operatively connected at its opposite end to vibrate said frame laterally, intermeshing gears carried by said shafts for rotating said needle-vibrating shaft at one-sixth the speed of rotation of said needle-reciprocating shaft, and means providing for adjustment 55 60 of one of said gears angularly about the axis of its shaft, thereby to adjust the timing of said eccentric.

6. In a sewing machine, stitch-forming mechanism including an endwise reciprocator and laterally vibratory needle-bar, a swinging frame in which said needle-bar is journaled for endwise reciprocation, means for reciprocating said needle-bar, a rotary needle-vibrating eccentric, means actuated by said eccentric and operatively connected to swing said frame laterally, and means for rotating said eccentric at one-sixth the speed of rotation of said needle-reciprocating shaft and in timed relation to effect the production of two substantially equal length stitches 70 75

and one relatively longer stitch in each direction of lateral vibration of said needle-bar.

7. In a sewing machine, in combination, an endwise reciprocatory and laterally vibratory needle-bar, a swinging frame in which said needle-bar is journaled for endwise reciprocation, a rotary needle-vibrating eccentric, means actuated by said eccentric and operatively connected to swing said frame laterally, means for rotating said eccentric, means for reciprocating said needle-bar a plurality of times in each direction of lateral vibration of said frame, a feed-dog, actuating mechanism for imparting operative work-advancing movements to said feed-dog, a rotary feed-controlling eccentric, means for rotating said feed-controlling eccentric in a continuous direction, and means actuated by said feed-controlling eccentric and operatively connected to said feed-actuating mechanism for controlling the work-feeding movements of said feed-dog.

8. In a sewing machine, in combination, an endwise reciprocatory and laterally vibratory needle-bar, a swinging frame in which said needle-bar is journaled for endwise reciprocation, a rotary needle-reciprocating shaft, operative connections with said shaft for reciprocating said needle-bar, a rotary needle-vibrating eccentric, means for rotating said needle-vibrating eccentric at one-sixth the speed of rotation of said needle-reciprocating shaft, means actuated by said eccentric and operatively connected to swing said frame laterally, a feed-dog, actuating mechanism for imparting operative work-feeding movements to said feed-dog, a rotary feed-controlling eccentric, means for rotating said feed-controlling eccentric at one-third the speed of rotation of said needle-reciprocating shaft, and means actuated by said feed-controlling eccentric and operatively connected to said feed-actuating mechanism for controlling the work-feeding movements of said feed-dog.

9. In a sewing machine, in combination, an endwise reciprocatory and laterally vibratory needle-bar, a swinging frame in which said needle-bar is journaled for endwise reciprocation, a rotary needle-vibrating eccentric, means actuated by said eccentric and operatively connected to swing said frame laterally, means for rotating said eccentric, means for reciprocating said needle-bar a plurality of times in each direction of lateral vibration of said frame, a feed-dog, actuating mechanism for imparting operative work-advancing movements to said feed-dog, a rotary feed-controlling eccentric, means for rotating said feed-controlling eccentric in a continuous direction, means actuated by said feed-controlling eccentric and operatively connected to said feed-actuating mechanism for controlling the work-feeding movements of said feed-dog, and means providing for relatively adjusting the timing of said needle-vibrating and feed-controlling eccentrics.

10. In a sewing machine, in combination, an endwise reciprocatory and laterally vibratory needle-bar, a swinging frame in which said needle-bar is journaled for endwise reciprocation, a rotary needle-reciprocating shaft, operative connections with said shaft for reciprocating said needle-bar, a rotary needle-vibrating shaft disposed crosswise of said needle-reciprocating shaft, a needle-vibrating eccentric carried by needle-vibrating shaft, a pitman having at one end a strap embracing said eccentric and operatively connected at its opposite end to vibrate

said frame laterally, intermeshing gears carried by said shafts for rotating said needle-vibrating eccentric at one-sixth the speed of rotation of said needle-reciprocating shaft, a feed-dog, actuating mechanism for imparting operative work-feeding movements to said feed-dog, a rotary feed-controlling shaft extending crosswise of said needle-reciprocating shaft, means for rotating said feed-controlling shaft at one-third the speed of rotation of said needle-reciprocating shaft, a feed-controlling eccentric rotatable with said feed-controlling shaft, and means actuated by said feed-controlling eccentric and operatively connected to said feed-actuating mechanism for controlling the work-feeding movements of said feed-dog.

11. In a sewing machine, in combination, an endwise reciprocatory and laterally vibratory needle-bar, a swinging frame in which said needle-bar is journaled for endwise reciprocation, a rotary needle-vibrating eccentric, means actuated by said eccentric and operatively connected to swing said frame laterally, means for rotating said needle-vibrating eccentric, means for reciprocating said needle-bar a plurality of times in each direction of lateral vibration of said frame, a work-advancing feed-dog, a feed-bar carrying said feed-dog, a rocking member having a guideway extending across the fulcrum-axis of said guideway, means for rocking said member once in opposite directions for each complete reciprocation of said needle, a slide-block shiftably disposed in said guideway and operatively connected to said feed-bar to transmit the rocking movements of said member to said feed-dog, a rotary feed-controlling eccentric, means for rotating said feed-controlling eccentric at one-third the speed of rotation of said needle-reciprocating shaft, and means actuated by said feed-controlling eccentric and operatively connected to shift said slide-block in said guideway.

12. In a sewing machine, in combination, an endwise reciprocatory and laterally vibratory needle-bar, a laterally swinging frame in which said needle-bar is journaled for endwise reciprocation, a rotary needle-reciprocating shaft, operative connections with said shaft for reciprocating said needle, a feed-dog, actuating means for imparting operative work-feeding movements to said feed-dog, needle-vibrating and feed-controlling shafts extending crosswise of said needle-reciprocating shaft, means for driving said needle-vibrating shaft and feed-controlling shafts at relatively different speeds both slower than the speed of rotation of said needle-reciprocating shaft, a needle-vibrating eccentric carried by said needle-vibrating shaft and operatively connected to vibrate said frame laterally, and a feed-controlling element carried by said feed-controlling shaft and operatively connected to said feed-dog actuating means for controlling the effective work-feeding movements of the feed-dog.

13. In a sewing machine, in combination, an endwise reciprocatory and laterally vibratory needle-bar, a laterally swinging frame in which said needle-bar is journaled for endwise reciprocation, a rotary needle-reciprocating shaft, operative connections with said shaft for reciprocating said needle, a feed-dog, actuating means for imparting operative work-feeding movements to said feed-dog, needle-vibrating and feed-controlling shafts extending crosswise of and disposed at opposite sides of said needle-reciprocating shaft, means for driving said needle-vibrating shaft at one-sixth the speed of rotation of said

needle-reciprocating shaft, a needle-vibrating element carried by said needle-vibrating shaft and operatively connected to vibrate said frame laterally, means for driving said feed-controlling shaft at one-third the speed of rotation of said needle-reciprocating shaft, a feed-controlling eccentric secured for rotation with said feed-con-

trolling shaft, and means actuated by said feed-controlling eccentric and operatively connected to said feed-dog actuating means for controlling the direction of the effective work-feeding movements of said feed-dog. 5
